CLAIM

The ornamental design for an earphone, as shown and described.

DESCRIPTION

FIG. 1 is a front, left perspective view of a first embodiment of an earphone showing my new design;
FIG. 2 is a rear, left perspective view thereof;
FIG. 3 is a top, left perspective view thereof;
FIG. 4 is a front view thereof;
FIG. 5 is a rear view thereof;
FIG. 6 is a left side view thereof;
FIG. 7 is a right side view thereof;
FIG. 8 is a top plane view thereof;
FIG. 9 is a bottom plan view thereof;
FIG. 10 is a front, right perspective view of a second embodiment of the earphone showing my new design;
FIG. 11 is a rear, right perspective view thereof;
FIG. 12 is a top, right perspective view thereof;
FIG. 13 is a front view thereof;
FIG. 14 is a rear view thereof;
FIG. 15 is a left side view thereof;
FIG. 16 is a right side view thereof;
FIG. 17 is a top plan view thereof; and,
FIG. 18 is a bottom plan view thereof.
